SELECTIVE HANDLE CONNECTION FOR FLOOR POLISHING MACHINES

Daniel A. Arones, Minneapolis, Minn., assignor to Advance Machine Company, Minneapolis, Minn., a corporation of Minnesota

Application March 10, 1955, Serial No. 493,382

4 Claims. (Cl. 306—12)

My invention relates to an improvement in floor polishing machines and more particularly to the handle thereof for moving the same over a surface and the connection of the handle to the machine whereby the machine may be selectively operated and used in various desirable ways.

It is an object of my invention to provide a handle and a selectable connection therefor for a floor polishing machine whereby the handle may be selectively locked in an approximately 45° position for treating floors by an experienced operator where the rotating action of the brush is utilized to propel the machine across the floor. It is a further object to provide a handle connection which also allows a selection of a floating or hinged up and down movement of the handle for the less experienced operator who pushes or pulls the unit across the floor. It is a further object to also provide the same handle connection which also automatically locks in a vertical position when the handle is moved into that position for storage of the machine or for tipping of the machine so that the same may be rolled and transported easily from place to place on the wheels mounted on the machine.

It is a further object of my invention to provide a vertically disposed quadrant member secured to the base of the machine and on which a latch member rides. The quadrant is provided with recesses into which the latch may be inserted and an upper shoulder which automatically directs the latch into an upper recess of the quadrant.

It is an additional feature to provide a spring biased latch member slidably and pivotally mounted on the lower end of the handle and having a catch member which is normally held in engagement with a shoulder formed adjacent a slot in the handle for a free floating of the handle but which is directed into the slot by a shoulder strategically placed on the upper portion of the quadrant which acts against the latch to move it automatically into the upper recess of the quadrant for rigid positioning of the handle.

I shall not here attempt to set forth and indicate all of the various objects and advantages incident to my invention, but other objects and advantages will be referred to in or else will become apparent from that which follows.

The invention will appear more clearly from the following detailed description when taken in connection with the accompanying drawings, showing by way of example a preferred embodiment of the inventive idea wherein like numerals are employed to designate like parts throughout.

In the drawings forming part of the application:

Figure 1 is a side view illustrating a floor machine with my new handle and selective connection construction thereon with the handle in the free floating position and the latch in raised position.

Figure 2 is a side view of my handle connection in locked vertical position with a portion of the floor machine shown.

Figure 3 is a side view similar to Figure 2 but with the handle locked into approximately a 45° position.

2

Figure 4 is a detailed perspective view of the end of the handle showing the slot detail thereof.

Figure 5 is a perspective view of the end of the handle connection in an opposite view to that shown in Figure 2.

5 Figure 6 is a view similar to Figure 5 but with the latch member in locked raised position allowing free handle movement up to the vertical position shown in Figures 2 and 5.

10 Figure 7 is an exploded detailed perspective view of the latch member and a portion of the slot detail with the latch in lowered position as in Figures 2 and 5.

Figure 8 is a rear view of a portion of the machine showing the handle connection.

15 Referring to the drawings in detail, my floor polishing machine selective handle connection A is mounted on the lower housing B of the machine C. Rotatably mounted under the housing B is the circular brush D. The housing B has rotatably mounted on the rear thereof the fixed wheels 10. Further, I provide the upright bracket 11 which has formed on the lower end thereof the right angular portions 12 through which the bolts 13 extend and secure into the housing B to support the bracket 11 in a normally vertical position. The bracket 11 has formed on the upper portion thereof the substantially arcuated or 20 quadrant portion 14 which has formed therein the lower notch 15 which is approximately 45° with respect to the base line of the bracket.

25 A notch 16 is formed in the upper part of the quadrant 14 and extending upwardly from the notch 16 is the shoulder 17. The notches 15 and 16 receive the latch shoulder portion hereinafter referred to as the handle portion 18, which has its counterpart 18', has formed on the lower end thereof the flattened portion 19 which includes the hole 20. The counterpart 18' is hinged at 18''. The handle portion 18 is pivotally mounted on the bracket 11 by means of the bolt 21 which passes through the flat washer 22, the bracket 11, the fibre washer 22', the hole 20 of the flattened portion 19, the flat washer 23, and the lock washer 24, and is secured by the nut 25.

30 I further provide the elongated slot 26 formed in the flattened portion 19 of the handle member 18. The slot 26 has formed on the one edge thereof the offset notch 27 which is formed with the lower shoulder 28, the oblique edge 29, and the upper shoulder 30. In connection with 35 the slot 26 I provide the latch member 31 formed with the upper threaded hole 32 and the lower threaded hole 33. Positioned against the inside of the flattened portion 19 opposite the latch 31 is the plate 34 through which extends the bolts 35 and 36.

40 The bolt 35 has positioned thereon the round collar 37 of a diameter whereby the bolt 35 may be moved up and down in the slot 26. The bolt 36 has mounted thereon the square collar catch member 38 which is slideable in the slot 26 and also movable into the offset notch 27 as hereinafter described. The collar 37 and catch member 38 are of a thickness slightly greater than the thickness of the flattened portion 19 so the latch 31 and the plate 34 do not bind against the portion 19 when the bolts 35 and 36 are tightened. The bolts 35 and 36 are 45 screwed into the holes 32 and 33 of the latch member 31, and the knob 39 is screwed onto the outer end of the bolt 36 to secure the same thereto.

50 Secured to the lower corner 40 of the plate 34 is the spring 41 the other end of which is secured to the flattened portion 19 at 42 to bias the plate 34 towards the offset notch 27 and generally downwardly towards the lower end of the flattened portion 19.

55 With the latch 31 secured in position by means of the bolts 35 and 36 the same may be secured in the "up" position, as in Figure 1, by lifting upwardly on the knob 39 whereby the collar 38 is lifted upwardly in the slot

26, and as a result the biasing of the spring 41, the collar 38 is drawn into the offset notch 27 and drawn against the shoulder 28 to keep the shoulder 43 of the latch member 31 in an upward position clear of the quadrant portion 14 of the bracket 11, so that the handle portions 18 and 18' may be pivoted freely from the point of shoulder 17 downwardly past the lower notch 15 if desired. As the latch shoulder 43 passes the notch 15, the same will not drop into the notch 15, for the latch is in the raised or upward position as heretofore described.

The inexperienced operator generally uses the machine with the latch 31 in the freely pivotal position last described, and as indicated in Figure 1, whereby the machine is moved over the floor by pushing or dragging the same with the handle.

The experienced operator may move the handle so that the latch 31 is opposite the lower notch 15 and then move the knob 39 against the biasing action of the spring 41 to allow the collar 38 to be drawn out of the offset notch 27. At this point the additional downward pull of the spring 41 will draw the collar 38 downwardly into the lower end of the elongated slot 26 against the bottom shoulder 30', and as a result the latch shoulder 43 can easily slip into the notch 15 to place the handle in rigid position on the machine as in Figure 3, at about 45°. In this latter locked position, the experienced operator can utilize the rotary motion of the brush D to self-propel the machine across the floor by simple manipulation well known in the art. The handle is changed from the above 45° locked position by lifting up on the knob 39 to lift the shoulder 43 from the notch 15. As a result the latch 31 is placed in the secured lifted position as in Figure 1 hereinbefore described where the shoulder 43 rides free of the edge of the quadrant 14 as the handle 18 is pivoted up and down.

As the handle is moved to the vertical position of Figure 2 to the notch 16 the forward edge 44 of the shoulder 43 contacts the shoulder 17, and this action automatically, and without further action by the operator, moves the collar 38 out of the offset notch 27 and into the bottom of the notch 26 against the shoulder 30' whereby the shoulder 43 slips into the notch 16 placing the handle 18 into an upright rigid position in which the same may be stored. In the last mentioned locked position of the handle, and of greater importance, the machine may be easily tilted backwardly onto the wheels 10 thereby raising the brush completely free of the floor and allowing the machine to be moved about on the wheels with the handle at about a 45° angle. With the handle in any other position the handle has to be additionally lowered and would then be too low for convenience with the brush free from the floor.

The invention is not to be understood as restricted to the details set forth since these may be modified within the scope of the appended claims without departing from the spirit and scope of the invention.

Having thus described the invention, what I claim as new and desire to secure by Letters Patent is:

1. In a mobile floor polishing machine having a motor supporting housing and an operating handle extending therefrom, the improvement for mounting the handle on the housing to allow selective floating or rigid positioning of the handle thereon, said improvement comprising an upright bracket mounted on said housing, a double ended handle member having one end pivotally connected to said upright bracket, a quadrant formed on said bracket having an upper and lower notch formed therein, a shoulder formed on said quadrant adjacent said upper notch, the lower portion of said handle end having an elongated slot formed therein and a slot offset from said first slot and connecting therewith, a latch member slidably mounted on said handle end including catch means

secured to said latch member extendable into said slot or said offset slot by manipulation by the operator or automatically by said shoulder when said latch member is caused to contact said shoulder, spring means for normally biasing said latch and said latch extension catch means generally downwardly and obliquely in relation to the longitudinal axis of said handle, and knob means secured to said latch for moving said catch means out of said slot of said handle and into said offset slot to permit said latch to ride above and free of said quadrant, said knob means also adapted to move said catch means from said offset slot into said elongated slot to allow said latch to engage said lower notch or said upper notch of said quadrant automatically when said latch is caused to contact said shoulder for rigid positioning of said handle on said housing in the position selected.

2. In a floor polishing machine having a housing and an operating handle extending therefrom, the improvement for mounting the handle on the housing, said improvement comprising a bracket mounted on said housing and having a handle member pivotally connected thereto, said bracket having notches formed therein, the lower end of said handle member having a slot formed therein, said handle having an offset slot extending from said slot, a latch slidably mounted on said handle and formed with a catch portion normally extending into said slot, spring means urging said latch downwardly on said handle slot and said catch portion towards said offset slot, and means for moving said catch into either said slot or said offset slot for engagement or non-engagement of said latch with said notches of said bracket.

3. In a floor polishing machine including a base and an operating handle extending therefrom, the improvement for mounting the handle on the base, said improvement comprising a bracket adapted to be mounted on said base, said bracket having upper and lower latch-receiving means thereon, a handle member pivotally mounted on said bracket, latch means having catch means formed thereon and slidably mounted on said handle member, said latch means engageable with said latch-receiving means of said bracket, said handle having slot and connecting offset slot means formed therein for receiving said catch means, means for urging said catch means generally downwardly in said slot means and biased towards said offset slot means, shoulder means on said bracket for moving said latch means to direct said catch means out of said offset slot means and into said slot means to allow said latch means to move into said upper latch receiving means.

4. In a mobile floor conditioning machine including a base and an operating handle extending therefrom, the improvement comprising a bracket mounted on said base, a handle member pivotally mounted on said bracket and having a slot formed therein, a catch member slidably mounted in said slot, shoulder means formed on said handle adjacent said slot, means for urging said catch member downwardly in said slot and in the direction of said shoulder means, means for moving said catch in said slot and into engagement with said shoulder means, spaced recesses formed in said bracket, a shoulder formed on said bracket adjacent the uppermost of said recesses for engagement with said catch moving means to automatically direct said catch into said slot from said shoulder means and allow said catch moving means to enter said uppermost recess of said bracket to maintain said handle in a rigid position.
